UNITED STATES PATENT OFFICE

RUSSELL J. ANDERSON, OF RACINE, WISCONSIN, ASSIGNOR TO BELLE CITY MALLEABLE IRON COMPANY, OF RACINE, WISCONSIN, A CORPORATION OF WISCONSIN

SKIMMER

Application filed August 15, 1930. Serial No. 475,482.

My invention relates to skimmers and especially to improvements for that type of skimmer used in removing slag and impurities from the surface of a bath of molten metal. As these skimmers are subjected in use to high temperatures, they burn out and lose their usefulness, necessitating frequent replacement and adding to the manufacturing burden to that extent.

I have proposed in my Patent No. 1,763,637 issued June 17, 1930, that these skimmers be water cooled so that the liquid acts as a circulating heat transfer agent and prevents burning out of the skimmers by protecting them in such manner.

The present invention relates to other forms of liquid cooled skimmers, the objects of the invention being to provide improved forms of skimmers which will be cheap to produce and in practice will satisfactorily perform their intended function without burning out or otherwise getting into disrepair.

Such objects may be achieved by the practicable embodiments of the invention herein chosen by way of example for purposes of illustration in the accompanying sheets of drawings, wherein:

Figure 1 is a top plan view of a skimmer; Figure 2 is a side elevational view of the same skimmer;

Figure 3 is an end elevational view of the skimmer;

Figure 4 is a top plan view of a similar but modified type of skimmer;

Figure 5 is a side elevational view of the modified form of a skimmer; and,

Figure 6 is an end elevational view of said modified skimmer.

In the first form of the invention illustrated in Figures 1, 2 and 3, the skimmer embodies a hollow, rectangular box-shaped skimmer head 10 which has connected to one face substantially intermediate of its ends, a pair of pipes 11 forming the shaft of the skimmer. Said pipes are in communication with the interior of the head and are preferably arranged in parallelism, with one pipe located on each side of the longitudinal cen-

ter line of the shaft as appears in Figure 1. Said pipes 11 where they meet the head are preferably curved to diverge outwardly, as shown at 12. The free ends of the pipe are joined by any appropriate connector 13 to receive a handle 14. Each pipe has associated therewith a lead nipple 15 and one of said nipples is provided with a control valve 16.

Obviously, in use the valve 16 will be opened to permit circulation of a cooling liquid, such as water, along one of the pipes 11, said liquid because of the curve 12 moving outwardly to the adjacent end of the head and thence flushing and washing the interior thereof as indicated by the arrows in Figure 1. Thence the water or other liquid is returned through the other pipe 11 in an obvious manner to complete the circulation by passing off through the outlet nipple 15. In this manner the cooling liquid functions as a heat transfer medium to maintain the skimmer relatively cooled whereby said skimmer is protected against burning out, as will be readily understood by those skilled in this art.

In the modified form appearing in Figures 4, 5 and 6 the shaft again comprises two parallel, spaced lengths of pipe 17 the free ends of which are appropriately joined by a connector 18 which carries the handle 19. The opposite, or other ends of these pipe lengths are again outwardly curved as at 20. Said curved pipe ends then turn laterally outwardly in opposite directions as shown at 21, thence downwardly at their ends as at 22 and inwardly again at the bottom to form a run of pipe 23 parallel and below the wings 21 to form the skimmer head. Thus, it can be seen a continuous length of pipe is formed into a unitary shaft and head structure. Each pipe length 17 carries a lead 24 one of which is provided with a control valve 25 so that a cooling fluid, such as water, may be circulated along one run 17 of the pipe, thence through the skimmer head portion of the continuous pipe, thence back along the other run 17 of the pipe and finally out through the outlet nipple 24 in an obvious manner. Here then is a simplified form of a skimmer tool

comprising a single length of pipe formed into a unitary shaft and head structure to permit free circulation of a cooling liquid to maintain the tool cooled whereby oxidization 5 and burning out thereof in use within a metal melting furnace will be effectually prevented.

From the above detailed disclosures the construction and use of the improved skimmers are clear, and it must also now be apparent that these skimmers achieve the desirable objects for the invention heretofore recited.

It is the intention to cover herein all such changes and modifications of the selected examples herein shown as do not depart from the spirit and scope of my invention which is expressed in the subjoined claims.

What I claim is:

1. In a skimmer, a hollow skimmer head 20 part, a shaft connected thereto, said shaft comprising two separated lengths of pipe lying laterally side by side with respect to each other and each communicating at one end with the hollow head, means joining said two pipe lengths at the other end, a handle portion connected to said joining means, and means for causing a cooling liquid to be circulated along one pipe length, thence through the head part, and back through the other pipe length.

2. In a skimmer, a skimmer head part, a shaft connected thereto said shaft comprising a pair of spaced, substantially parallel pipes arranged substantially side by side and connected to the head, and means whereby a cooling liquid may be circulated through one pipe, thence through the head part and back through the other pipe.

3. In a skimmer, a skimmer head part, a shaft connected thereto, said shaft comprising a pair of pipes, spaced apart side by side and each connected with a curved portion to the head part, and means whereby a cooling liquid may be circulated along one pipe, thence through the head part, and back through the other pipe.

4. A skimmer comprising a hollow skimmer head part a pair of pipe lengths arranged side by side to form a shaft, said pipe length communicating with the interior of the head part whereby a cooling liquid may be circulated through the shaft and head part.

5. A skimmer comprising a hollow elongated skimmer head part, a shaft comprising a pair of pipe lengths arranged side by side and spaced apart on opposite sides of the shaft center line, said pipe lengths each merging in an outwardly flared curve with 60 the head part to communicate with the interior thereof, whereby a cooling liquid may be circulated through the shaft and head.

6. A skimmer formed of a unitary length of pipe into a shaft part and a head part.

65 7. A skimmer comprising a pipe having

a shaft part formed of two lengths of the pipe arranged side by side, each length then bent outwardly to form wings, each wing then bent downwardly and joined below the wings to form a skimmer head part.
